UNITED STATES PATENT OFFICE.

GUSTAV A. SCHETTLER, OF LEEDS, ENGLAND, AND OSKAR BÖTTGER, OF FRANKFORT-ON-THE-MAIN, GERMANY, ASSIGNORS TO THE TURNER TANNING MACHINERY COMPANY, OF PORTLAND, MAINE, A CORPORATION OF MAINE.

MACHINE FOR OPERATING UPON HIDES, SKINS, LEATHER, AND OTHER SIMILAR PIECES OF WORK.

Application filed September 8, 1926, Serial No. 134,192, and in Germany October 30, 1925.

This invention relates to machines for operating upon hides, skins, leather and other similar pieces of work and is illustrated as embodied in a shaving machine for operating upon leather. It is to be understood, however, that various features of the invention are not limited in their application to shaving machines but may have other applications and uses.

10 As heretofore constructed, shaving machines have commonly comprised a work supporting and work presenting roll mounted so as to be freely rotatable upon its supporting shaft, the arrangement being such that the 15 operator directly controlled the feeding of the work. This construction required the exercise of very considerable skill on the part of the operator and involved also much laborious effort in attempting to secure uniformity 20 in shaving operations upon all the various portions of the work.

It is an object of the invention to provide an improved shaving machine which will make less demands on both the strength and 25 the skill of the operator while enabling him to secure better and more uniform quality of work.

To this end and in accordance with important features of the invention, there is provided in the illustrated machine power driven 30 means under the control of the operator for feeding the work to the work treating tool wherein a single manually controlled member permits the operator to control directly the 35 movements of a work feeding roll between work receiving and work presenting positions and to control also the application of power 40 to drive the roll at a uniform rate while it is in work presenting position, whereby the 45 feeding of the work is accomplished uniformly without laborious effort on the part of the operator. In the illustrated construction, connections are provided whereby a treadle mechanism is utilized to cause movement 50 of the roll between work receiving and work presenting positions and to effect disconnection of the driving means for the roll after it has moved away from the work treating tool and to reconnect the driving means before the roll again reaches work presenting 55 position with respect to the treating tool.

The advantage of this arrangement resides in the fact that the operator is assisted in feeding the work at a uniform rate even while it is being retracted from the tool and also while 55 being moved into contact with the tool, thus reducing to a minimum the danger of injury to the work during the described movements of the roll. Preferably and as shown, connection and disconnection of the roll with respect 60 to its driving means are effected through the operation of frictional contacting members controlled by the treadle so that the power driving means for the roll is thrown into and out of operation in timed relation to the 65 movements of the work support when shifting between work receiving and work presenting positions. As shown, the frictional contacting member in the roll driving means comprises a wheel having a frictional peripheral surface arranged to co-operate with a friction face on a disk, the axis of the disk being at a right angle to the axis of the wheel.

Another important feature of the invention resides in the provision, in the organization 75 shown, of improved means for changing the speed of the work supporting and presenting roll to suit the skill and convenience of the operator in shaving operations upon hides and skins and to enable him to vary the speed 80 in accordance with the thickness of the layer to be shaved from the piece of work. Conveniently this adjustment is secured in the illustrated construction by relative movement between the wheel and the disk which form the 85 frictional driving connection for the work supporting and work presenting roll. By this arrangement a great variety of adjustments may be secured suited to the skill of each individual operator and without affecting the 90 control of the driving means for the roll or the extent of movement of the treadle utilized in effecting both the application of power to the roll and the bodily movements of the roll between work receiving and work presenting 95 positions.

These and other features of the invention will be described in detail in the specification and pointed out in the appended claims.

In the drawings,

Fig. 1 is a view, in side elevation and partly in section, of a shaving machine illustrating

a preferred embodiment of the invention; and

Fig. 2 is a detail view showing the frictional driving means for the work feeding 5 roll.

In the illustrated shaving machine there is provided a bladed cylinder 10 secured to a shaft 12 mounted in bearings provided by the frame 14 of the machine, the shaft 12 being driven by a belt 16 passing around a pulley on the shaft 12 and also around pulley 18 on power shaft 20. It will be understood that the power shaft 20 may be driven from any suitable source of power.

15 For supporting hides, skins or other work and presenting it to the bladed cylinder 10 there is provided a roll 22 secured to a shaft 24 mounted in the upper ends of two lever arms, one of which is shown at 26 (Fig. 20 1) both lever arms being pivoted upon a transverse shaft shown at 28. For moving the roll 22 toward the bladed cylinder 10 there is provided a treadle 30 having connections with the levers 26 comprising a link 32 pivotally connected to the lower end of one of the levers 26, the said link being connected at its other end by a pivot to an upwardly extending arm 34 rigid with the treadle 30. For returning the treadle 30 to initial position 25 there is provided, in the construction shown, a spring 36 interposed between the treadle and the base of the machine.

Means is provided for causing rotation of the roll 22 in the direction of the arrow in Fig. 1 whereby the work is fed into the machine while it is being operated upon by the bladed cylinder 10. In the illustrated construction this driving means for the roll 22 comprises a sprocket 40 secured to the shaft 24 around which passes a chain 42 which also engages a second sprocket 44 on a shaft 46 journaled for rotation in bearings in the machine frame 14. Secured to the shaft 46 is a worm gear 48 which is constantly in mesh 40 with a worm 50 secured to a shaft 52 supported in a bearing 54 in the machine frame.

Means is provided for driving the shaft 52 through frictionally engaging members, the construction having advantages which will be 50 hereinafter pointed out. As shown, the driving means for the shaft 52 comprises a shaft 60 arranged in axial alinement with the shaft 52 in bearings 62 in the machine frame. Secured to the forward end of the shaft 60 is a sleeve 64 having a bore slidably to receive the rear end portion of the shaft 52, the adjacent ends of the two shafts 52 and 60 being normally spaced from each other. In order that the shaft 52 may be driven from the 55 shaft 60 the sleeve 64 is provided with a groove to receive a key 66 secured to the shaft 52. Keyed to the shaft 60 adjacent to its rear end for sliding movement thereon is a disk 70, the shaft 60 having a collar 72 (Fig.

2) for limiting movement of the disk 70 along the shaft 60 under the action of a spring 74 which is interposed between the disk and a second collar 76 secured to the shaft 60. Arranged at a right angle to the shaft 60 is a shaft 80 supported in bearings furnished by a block 82 and mounted upon the shaft is a pulley 84 arranged to be driven by a belt 86 which passes also over a second pulley 88 located on and secured to the main shaft 20 of the machine. Secured to one end of the shaft 80 is a driving wheel 90 having a friction-surfaced member 92 adapted to contact with a friction surface on the disk 70 to drive the latter. It will be readily understood that the two frictionally contacting members 70, 90 provide a friction clutch which may be caused to engage or disengage promptly and safely at any point in the operation on the work and in predetermined time relation to the movement of the work feeding roll 22 into and out of co-operative relation with respect to the cylinder 10. By reason of the spacing between the ends of the shafts 52 and 60 the compression tension on the spring 74 may be gradually increased as the work is pressed more firmly by the roll 22 against the cylinder 10, thereby insuring proper driving of the roll 22 through the friction clutch as the pressure on the work increases. There is thus provided a simple and inexpensive clutch device which has the advantage of being regulatable to the bodily movements of the work supporting and feeding roll 22 so that the latter continues to rotate while the work is in contact with the cylinder 10, as will be hereinafter described.

Preferably, and as shown, the driving wheel 90 is adjustable toward and from the center of the disk 70 to vary the speed of rotation of the disk 70 and therefore of the shafts 60 and 52. The means for moving the driving wheel 90 in its adjustment with respect to the disks 70 comprises a slidable mounting for the block 82 which is dovetailed upon a projection 94 extending from a portion of the frame 14 of the machine. Passing through the block 82 is a threaded spindle 96 provided with a hand wheel 98 so that upon rotation of the spindle 96 the block 82 and the parts carried thereby are moved in a direction axially of the shaft 80 whereby the wheel 90 is moved toward or from the center of the disk 70. It will be understood that adjustment of the wheel 90 with respect to the disk 70 will take place while the disk 70 is out of contact with the wheel and that this adjustment of the disk and wheel relatively to each other provides for a regulation of the speed of the disk designed to secure within limits a very wide variation in the speed of the disk, thus providing for adjustment of the speed to suit the skill and requirements of any operator.

For moving the shaft 60 axially to cause contact of the disk 70 with the wheel 90 there is provided a connection between the shaft 60 and the treadle 30 so that upon depressing 5 the treadle to move the feeding roll 22 to present the work to the bladed cylinder power is also transmitted to rotate the feeding roll 22. In the construction shown, this connecting means between the shaft 60 and the 10 treadle 30 comprises a ring 100 mounted in a groove in the sleeve 64 (so that the latter may rotate in the ring) and having bosses (not shown) for connection with a forked extension 102 of the lever arm 34 of the treadle 30. 15 Upon depressing the treadle 30 the shaft 60 is caused to move endwise within its bearings 62 to press the disk 70 yieldingly against the wheel 90 whereby power is communicated from the main shaft 20 to the shaft 60. Upon 20 inspection of Fig. 1 it will be observed that even a slight movement of retraction of the roll 22 will carry the work away from the cylinder 10 while the roll 22 is being driven due to the fact that the disk 70 is still pressed 25 by spring 74 against the wheel 90. It will be observed also that depression of the treadle 30 causes the work supporting and feeding roll 22 to move toward the bladed cylinder 10 to present the work thereon to the said cylinder, the parts being so arranged that before the work is pressed against the bladed cylinder 10, the roll 22 is power driven by the 30 driving means just described so that feeding of the work will be facilitated from the very 35 beginning of the shaving operations. Likewise the roll 22 moves away from work presenting position with respect to the cylinder 10 before the feed of the roll is discontinued. The arrangement described reduces to a minimum 40 the danger of injury to the work since the latter is not allowed to remain stationary while in contact with the bladed cylinder 10.

In operating with the machine illustrated in the drawings a piece of work such as a 45 calf skin is placed over the feeding roll 20 with the forward end portion of the work resting upon the curved surface of the roll 22 opposite to the surface of the bladed cylinder 10. Upon stepping on the treadle 30 50 the feed roll 22 moves toward the bladed cylinder 10, the roll starting its feeding rotation before the work contacts with the bladed cylinder. During the engagement of the bladed cylinder with the work backed by the 55 feeding roll 22 the work is fed downwardly between the roller and cylinder while the bladed cylinder operates at relatively high speed to shave the portions of the work presented during the feeding in of the work. 60 As soon as one portion of the work has been operated upon the operator releases the treadle 30 in order to shift the work laterally and to retract it, thereby presenting a new portion of the work to the operation of the cylinder 10. Should it be desired to change 65

the speed of the feeding roll 22 to secure a more rapid or a less rapid feeding in of the work, proper manipulation of the hand wheel 98 may be carried out whereby the wheel 90 is moved toward or away from the periphery 70 of the disk 70.

Having described our invention, what we claim as new and desire to secure by Letters Patent of the United States is:—

1. In a machine for operating on hides, skins, leather, and other like pieces of work, a tool for operating on a piece of work, work supporting and feeding means movable between work receiving and work presenting positions relatively to the tool, power means for operating said means to feed the work, and manually operable means constructed and arranged to enable the operator to control directly the bodily movement of the work supporting and feeding means between work receiving and work presenting positions and also to control connection and disconnection of said means with respect to its power driving means, the last-recited means comprising a direct connection between the manually operable means and the said power means. 75 80 85 90

2. In a machine for operating on hides, skins, leather, and other like pieces of work, a tool for operating on a piece of work, a roll movable between work receiving and work presenting positions relatively to the tool, power means for driving the roll, and treadle means constructed and arranged to enable the operator to control directly the bodily movement of the roll between work receiving and work presenting positions and also to control connection and disconnection of the roll with respect to its power driving means, said treadle means having a direct connection 100 105 with said power means. 95

3. In a machine for operating on hides, skins, leather, and other like pieces of work, a tool for operating on a piece of work, a roll movable between work receiving and work presenting positions relatively to the tool, power means for driving the roll, means under the control of the operator for effecting bodily movement of the roll between work receiving and work presenting positions, and a direct connection between the operator-controlled means and said power means for causing connection and disconnection of the roll with respect to its power driving means in timed relation to the recited 110 115 movements of translation of the roll. 120

4. In a machine for operating upon hides, skins, leather, and other like pieces of work, a rotary tool, a roll for supporting and presenting work to the tool, means for supporting the roll for movement toward and from the tool, power means for driving the roll to feed the work past the tool, and manually operable means for moving the roll to work presenting position and for causing discon- 125 130

nection of the roll with respect to its power driving means after the roll starts its movement toward work receiving position.

5. In a machine for operating upon hides, skins, leather, and other like pieces of work, a rotary shaving tool, a roll for supporting and presenting work to the tool, means for supporting the roll for movement toward and from the tool, power means for driving the roll to feed the work past the tool, and manually operable means for causing bodily movement of the roll between work receiving and work presenting positions and also for effecting operation of the power means for driving the roll before the latter reaches work presenting position and disconnection of the power means from the roll after the latter starts its movement toward work receiving position.

10 15

6. In a machine for operating upon hides, skins, leather, and other like pieces of work, a rotary tool, a roll for supporting and presenting work to the tool, means for supporting the roll for movement toward and from the tool, power means for driving the roll to feed the work past the tool, and manually operable means for moving the roll to work presenting position and for causing operation of the power means for driving the roll before the latter reaches work presenting position.

20 25

7. In a machine for operating upon hides, skins, leather, and other like pieces of work, a rotary shaving tool, a roll for supporting and presenting work to the tool, means for supporting the roll for movement toward and from the tool, power means for driving the roll to feed the work past the tool, yielding means tending constantly to move the roll to work receiving position, and manually operable means for moving the roll against the action of the yielding means to work presenting position and for effecting operation of the power means for driving the roll before the latter reaches work presenting position, and disconnection of the power means from the roll before the latter reaches work receiving position.

30 35

8. In a shaving machine, a rotary bladed cylinder for performing shaving operations upon a piece of leather, a roll for supporting and presenting a piece of leather to the bladed cylinder, said roll being bodily movable between work receiving and work presenting positions, power means under the control of the operator for driving the roll at a uniform rate to feed the work past the cylinder, a treadle for causing bodily movement of the roll between work receiving and work presenting positions, said power means comprising a friction clutch, and a connection between the treadle and the clutch arranged to increase the driving friction of the clutch as the pressure is increased on the work between the roll and the tool.

40 45

50 55

60 65

9. In a machine for operating upon hides, skins, leather, and other like pieces of work, a rotary tool, a roll for supporting and presenting a piece of leather to the tool, said roll being bodily movable between work receiving and work presenting positions and for throwing in the clutch to effect operation of the power means for driving the roll in timed relation to the recited movements of translation of the roll.

70 75

10. In a machine for operating upon hides, skins, leather, and other like pieces of work, a rotary tool, a roll for supporting and presenting a piece of leather to the tool, said roll being bodily movable between work receiving and work presenting positions, power means for driving the roll, said means comprising a friction clutch, and manually controllable means for causing bodily movement of the roll between work receiving and work presenting positions and for throwing in the friction clutch to effect operation of the power means for driving the roll in timed relation to the recited movements of translation of the roll.

80 85

90 95

11. In a machine for operating upon hides, skins, leather, and other like pieces of work, a tool for operating on a piece of leather, work supporting and feeding means bodily movable between work receiving and work presenting positions, power means for operating said means to feed the work at a uniform rate comprising a clutch, and a treadle for causing bodily movement of the work supporting and feeding means between the recited positions and operation of the clutch to effect driving of the roll in timed relation to the described movements of translation of the work supporting and feeding means.

100 105

12. In a shaving machine, a rotary bladed cylinder for operating on a piece of leather, a roll for supporting a piece of leather for the action of the bladed cylinder, said roll being bodily movable between work receiving and work presenting positions, power means for driving the roll at a uniform rate comprising a clutch, and a treadle for causing movement of the roll between the recited positions and operation of the clutch to effect driving of the roll while in work presenting position.

110 115

120

13. In a shaving machine, a rotary bladed cylinder for operating on a piece of leather, a roll for supporting a piece of leather for the action of the bladed cylinder, said roll being bodily movable between work receiving and work presenting positions, power means for driving the roll comprising a clutch, and a treadle for causing movement of the roll into work presenting position and operation of the clutch to effect driving of the roll prior to

125 130

the completion of its movement into work presenting position.

14. In a shaving machine, a rotary bladed cylinder for operating on a piece of leather, a roll for supporting the piece of leather for operation on the cylinder, power means for driving the roll while the latter is in work presenting position, said means comprising a clutch, means under the control of the operator for moving the roll to work receiving position and for throwing in the clutch to effect rotation of the roll, and manually operable means for varying the speed of the roll.

15. In a shaving machine, a rotary bladed cylinder for operating on a piece of leather, a roll for supporting the piece of leather for operation on the cylinder, power means for driving the roll while the latter is in work presenting position, said means comprising a clutch, means under the control of the operator for moving the roll to work receiving position and for throwing in the clutch to effect rotation of the roll, and manually operable means for adjusting the clutch to vary the speed of the roll.

16. In a shaving machine, a rotary bladed cylinder for operating on a piece of leather, a roll for supporting the piece of leather for operation by the cylinder, power means for driving the roll while the latter is in work presenting position, said means comprising a friction clutch, means under the control of the operator for moving the roll to work receiving position and for throwing in the clutch to effect rotation of the roll, and means for adjusting the clutch to vary the speed of the roll.

17. In a shaving machine, a rotary bladed cylinder for operating on a piece of leather, a roll for supporting a piece of leather for the operation of the cylinder, said roll being movable between work receiving and work presenting positions, power means for driving the roll comprising a wheel driven from any suitable source of power, a disk movable to present one of its faces in contact with the periphery of the wheel, a shaft arranged to be driven by the disk, and a treadle having connections with the roll and with the shaft to move the latter axially, whereby operation of the treadle causes the roll to move to work presenting position and the disk to move into contact with the wheel thereby effecting power operation of the roll in timed relation to the movements of the translation of the roll.

18. In a shaving machine, a rotary bladed cylinder for operating on a piece of leather, a roll for supporting a piece of leather for the operation of the cylinder, power means for driving the roll to feed the piece of leather past the cylinder, said means comprising a two-part clutch, and a manually operable member for moving the roll to work presenting position with respect to the bladed cylinder.

der, the manually operable member having a connection with one of the clutch parts, and the construction and arrangement being such that operative movement of the manually operable member causes engagement of the clutch parts before the roll reaches work presenting position with respect to the bladed cylinder.

19. In a shaving machine, a rotary bladed cylinder for operating on a piece of leather, a roll for supporting the piece of leather for the operation of the cylinder, power means for driving the roll to feed the piece of leather past the cylinder, said means comprising a two-part friction clutch, a treadle for moving the roll to work presenting position with respect to the bladed cylinder, said power means comprising an axially movable shaft arranged to operate one of the clutch parts and to transmit power from the clutch, and a connection between the treadle and the axially movable shaft to cause relative movement between the clutch parts to initiate rotation of the roll before it reaches work presenting position with respect to the bladed cylinder.

20. In a shaving machine, a rotary bladed cylinder for operating on a piece of leather, a roll for supporting the piece of leather for the operation of the cylinder, power means for driving the roll to feed the piece of leather past the cylinder, said means comprising a friction clutch consisting of a wheel having a friction surface on its periphery and a disk having a face for contact with the periphery of the wheel, said power means comprising also an axially movable shaft arranged to carry the disk and to press it yieldingly against the wheel upon movement of the shaft in one direction, a treadle for moving the roll to work presenting position with respect to the cylinder, and a connection between the treadle and the axially movable shaft to operate the latter in timed relation to the work presenting movement of the roll.

21. In a shaving machine, a rotary bladed cylinder for operating on a piece of leather, a roll for supporting the piece of leather for the operation of the cylinder, power means for driving the roll to feed the piece of leather past the cylinder, said means comprising a friction clutch, consisting of a wheel having a friction surface on its periphery and a disk having a face for contact with the periphery of the wheel, said power means comprising also an axially movable shaft arranged to carry the disk and provided with spring means to press the disk yieldingly against the wheel upon movement of the shaft in one direction, a treadle for moving the roll to work presenting position with respect to the cylinder, and connections between the treadle and both the roll and the shaft to move the roll and shaft simultaneously, the arrangement being such that the greater the travel of the roll toward the cylinder the

greater the yielding pressure of the disk against the wheel.

22. In a shaving machine, a rotary bladed cylinder for operating on a piece of leather, power means for rotating the cylinder, a roll for supporting and feeding the piece of leather for operation by the cylinder, power means for driving the roll while the latter is in work presenting position, said means comprising a friction clutch, and means under the control of the operator for throwing the clutch out or in to effect rotation of the roll,

the construction and arrangement being such that the driving of the roll may be discontinued at any desired point in the operation 15 on a piece of leather.

In testimony whereof I, the said GUSTAV A. SCHETTLER, have signed my name to this specification.

GUSTAV ADOLPH SCHETTLER.

In testimony whereof I, the said OSKAR BÖTTGER, have signed my name to this specification.

OSKAR BÖTTGER.
